CLAIM

The ornamental design for a bottle cap, as shown and described.

DESCRIPTION

FIG. 1 is a top perspective view of our bottle cap in accordance with our new design;

FIG. 2 is a front view thereof, with rear, left-side elevational and right-side elevational views being identical;

FIG. 3 is a top plan view thereof;

FIG. 4 is a bottom view thereof; and,

FIG. 5 is a cross-sectional view taken along the diametrical line 5-5 of FIG. 3.

The broken lines in the figures depict environmental subject matter only and form no part of the claimed design.
